UNITED STATES PATENT OFFICE.

FRED L. MACKENZIE, OF BEVERLY, MASSACHUSETTS, ASSIGNOR TO UNITED SHOE MACHINERY COMPANY, OF PATERSON, NEW JERSEY, A CORPORATION OF NEW JERSEY.

MACHINE FOR INSERTING FASTENINGS.

1,070,272.

Specification of Letters Patent. Patented Aug. 12, 1913.

Original application filed February 8, 1909, Serial No. 476,718. Divided and this application filed November 29, 1911. Serial No. 663,014.

To all whom it may concern:

Be it known that I, FRED L. MACKENZIE, a citizen of the United States, residing at Beverly, in the county of Essex and State 5 of Massachusetts, have invented certain Improvements in Machines for Inserting Fastenings, of which the following description, in connection with the accompanying drawings, is a specification, like reference characters 10 acting on the drawings indicating like parts in the several figures.

This invention relates to machines for inserting fastenings and particularly to fastening feeding mechanisms for use in machines 15 for inserting previously formed fastenings, machines of this type being usually provided with a raceway down which the nails or other previously formed fastenings gravitate into proximity to the inserting mechanism, and a rotating hopper or other means 20 for keeping the raceway filled with fastenings.

When a machine for inserting previously formed fastenings is to be operated at high 25 speed, it is important that the fastenings be uniformly positioned in the raceway so that the separating mechanism will always deliver a fastening to the inserting mechanism. It is furthermore important that the 30 raceway be supplied with fastenings as rapidly as possible to avoid the necessity for making the raceway unduly long. Various devices have been proposed and have been employed for insuring the proper delivery 35 of the fastenings to the raceway, and a number of these have been comparatively satisfactory in operation.

One of the most common types of mechanisms for causing the nails or other fastenings to be properly positioned in the raceway, as they are delivered thereto, is a rotary toothed wheel having imparted to it a continuous rotating movement. It is found, however, in operation that this type of mechanism is sometimes ineffective when the nails or other fastenings are in certain positions upon the raceway, so that the feeding of the nails down the raceway may be delayed for some time owing to the failure of the clearing device to dislodge a misplaced nail.

Having regard to the difficulties above pointed out and to the desired ends to be attained, I have discovered that a rotary raceway clearer which has imparted to it an in-

termittent motion of variable speed is most 55 effective in keeping the receiving end of the raceway clear and in insuring uniform positioning of the fastenings in the raceway. In the illustrated preferred embodiment of the invention the intermittent operation of 60 the raceway clearing mechanism is obtained through the use of a Geneva stop mechanism. Although it will be understood that, in its broadest aspects, the invention is not limited to the employment of this particular mechanism, 65 in view of the superior results obtained by the peculiar motion imparted to the clearing wheel by the Geneva stop mechanism, it is my intention particularly to claim the use of this mechanism in combination with a rotary raceway clearing device. 70

In the accompanying drawing is shown a broken side elevation of so much of the nail supplying mechanism of a loose nailing machine as is necessary to illustrate the application of my invention thereto, one of the hoppers being removed to show the nail receiving end of the raceway.

Upon a shaft 208, which is illustrated and more fully described in my co-pending application Serial No. 476,718, filed February 8, 1909, of which application the present application is a division, is mounted a pinion 240 which meshes with an annular gear 242 formed upon one of the hoppers, whereby 80 when the hoppers are operated there is imparted thereto a continuous, as distinguished from an intermittent, rotating movement, the nail feeding mechanism herein shown being intended to feed nails to a double raceway and comprising, as more fully described 85 in the co-pending application of George Goddu, Serial No. 476,649, filed February 8, 1909, a hopper upon which the annular gear 242 is carried and a second hopper 90 driven, from said first-mentioned hopper. The shaft 208 has also attached to it a pin wheel 244 of a Geneva stop mechanism. The counter shaft upon which the raceway clearer 238 is mounted has attached to it 95 the star wheel 246 of the Geneva stop mechanism. The pin 248 upon the pin wheel 244 entering successively the slots 250 in the star wheel 246 effects at each rotation of the shaft 208 one-sixth of a rotation of the raceway clearer 238. This intermittent movement of the raceway clearer 238 is very effective in removing a misplaced nail from 100 105

the upper end of the raceway, since the blow which it gives the misplaced nail is very quick and much more effective than the continuous movement of a constantly rotating clearing wheel. Moreover, it will be noted that the movement of the clearing wheel will be of varying angular velocity, the velocity being greatest at about the middle of the movement. This variable speed movement is also especially effective in keeping the receiving end of the raceway free from misplaced nails.

Having described my invention, what I claim as new and desire to secure by Letters Patent of the United States is:—

A machine of the class described having,

in combination, a raceway, a hopper, means for continuously rotating said hopper, a toothed wheel for clearing misplaced fastenings from the upper end of said raceway, and means for imparting to said toothed wheel intermittent rotary movement of varying angular velocity comprising Geneva stop mechanism interposed between the hopper rotating means and said toothed wheel.

In testimony whereof I have signed my name to this specification in the presence of two subscribing witnesses.

FRED L. MACKENZIE.
